COMBINATION HOLDER

Jacob Armin Bender, North Bergen, N. J.

Application March 30, 1939, Serial No. 264,963

1 Claim. (Cl. 30—339)

This invention relates to a combination handle and holder including different types of devices for holding interchangeable tools of different characters for many different practical uses, as well as for handling work pieces and for holding other objects in a large number of instances, to a convenient one-piece non-slip handle, and to a means and method capable of being applied in making the same and numerous other articles of similar structure.

An object of my invention is to produce a device of this character which is preferably formed of a single strand of wire of suitable nature to provide a convenient one-piece non-slip handle for holding new and old safety razor blades, cutters, files, saws and tools of other characters for many different practical uses.

Another object of my invention is to produce a device of this character which will afford a convenient and positive grip for the hand of the operator, and which is provided with a simple means suitably shaped and positioned so that a razor blade, file, saw, or other tool, or object may be held firmly in place.

Another object of my invention is to produce a device of this character which is provided with a simple self-locking retaining means that can be released or adjusted at will with ease and speed and which will permit the adjustable extension of any desired kind of tool for different practical uses in many instances.

Another object of my invention is to produce a device of this character wherein an interchangeable tool may be held firmly in different positions for desired depth of cut and special uses, and may be maintained in good working condition.

Another object of my invention is to produce a device of this character which is designed of a minimum number of component parts which will permit various modifications in construction, which is provided with a simple means for attachment or for hanging up, which will also afford a tension clip so that may be readily and conveniently disposed of.

With these and other objects and advantages in view, the mechanical features of construction, combination and arrangements of parts of the devices of my invention will be clearly described hereinafter, illustrated in the accompanying drawing, which disclose the preferred embodiments of my invention.

Now referring to the drawing:

Figure 1 is a longitudinal cross-section of one preferred form of devices of my invention show-

ing a suitable razor blade arranged in preferred position.

Figure 2 is a longitudinal cross-section of another preferred example of devices, without a loop, showing a file in attached position.

Figure 3 is a side view of an interchangeable cutter, which is formed with openings suitably arranged to facilitate the adjustable extension of the tool in connection with the combination handle and holder.

Figure 4 is a side view of another preferred design of an interchangeable file.

Figure 5 is a side view of a preferred design of an interchangeable saw.

Figure 6 is a detail cross-sectional view of the combination handle and holder as shown in Fig. 1.

Figure 7 is a detail cross-sectional view of another preferred form of the device.

Figure 8 is a detail cross-sectional view of a triangular handle and holder.

Figure 9 is a detail cross-sectional view of a circular handle and holder.

Figure 10 is a detail cross-sectional view of a semi-circular handle and holder.

Throughout the several views of the preferred forms of my devices in the drawing forming a part of this specification like numerals designate like parts.

The combination handle and holder constituting the subject-matter of this invention comprises a tubular casing 1 which is preferably formed of a single strand of wire coiled as shown, providing a positive grip for the hand of the operator. A hook 2 is formed at one end, suitably shaped and positioned so that a razor blade 5, or any tool, or work piece, may be held firmly in place. The retaining hook is of the snap-on type, holding the blade or tool firmly under tension, yet capable of quick release or adjustment. 40 A loop 3 in the other end of the casing provides means for attachment to a key ring, etc., or for hanging it up. This loop may also be moved and suitably arranged to provide a tension clip, as indicated by the dotted lines 4, for quick attachment, in a large number of instances, so that the device may be readily and conveniently disposed of. In a modified embodiment of the invention which is likewise capable of embodiment in other and varied constructional forms, 50 similar to that as shown by Fig. 2, a file is securely held in working position while one end of the holder is closed. The file is formed with a suitable opening or notch 6 to receive the hook 2. In Fig. 3, an interchangeable cutter is formed 55

with several openings suitably spaced from each other, to facilitate the adjustable extension of the cutter or any tool that may be employed for special or general uses in connection with the 5 combination handle and holder. In Fig. 4, an interchangeable file is adapted for delicate work and for attachment to the handle and holder. In Fig. 5, an interchangeable saw is adapted for attachment to the handle and holder. Figs. 10 6, 7, 8, 9 and 10 show the preferred shapes respecting the cross-section of the devices of my invention.

In order to make the tubular casing, or any 15 constructional portion thereof, entirely rigid with any desired coating or finish, the surface of the material should be properly treated with a suitable chemical solution that will render the material metallic clean without attacking or injuring the mechanical strength of the construction. By passing the casing through a bath of 20 suitable solder, the desired rigid structure may be obtained. The device may be plated, enameled, rubberized with a most attractive finish. During and after the process of soldering or in 25 the course of other treatments, special care should be taken to maintain the normal condition, and when desired, the fluted appearance of the devices.

In operation, my device can be easily manip-

ulated. It commends itself by reason of its simplicity, adjustability, pleasing appearance and low cost. It may be employed for countless practical uses in the home, workshop, office and factory, as it is widely adaptable to almost every 5 kind of small tool, work pieces and other objects.

It is to be understood that the preferred embodiments and form of my invention herewith described and shown in the accompanying drawing are to be taken as illustrative and not limitative thereof and that various changes relative to material, size, shape, details of construction, modifications, combination and arrangements of parts may be resorted to without departing from the spirit of the invention or the scope of the 10 15 subjoined claim.

Having thus described my invention, I claim:

In a device of the character described, the combination of a tubular casing and a tool, said tubular casing produced of a single strand of 20 wire and adapted for engaging with said tool, said tool having an opening, said tubular casing having a movable hook at one end projecting through said opening of said tool, said movable hook of said tubular casing adapted for retaining 25 said tool under tension in any position permitting adjustment for locking and holding said tool in its selected position.

JACOB A. BENDER.
